[57] CLAIM

The ornamental design for an indicator board, as shown and described.

DESCRIPTION

FIG. 1 is a front elevational view of an indicator board showing my new design;

FIG. 2 is a rear elevational view thereof, with the broken line showing for illustrative purposes only and forming no part of the claimed design;

FIG. 3 is a top plan view thereof;

FIG. 4 is a bottom plan view thereof;

FIG. 5 is a right side elevational view, the left side

elevational view being a mirror image thereof;

FIG. 6 is a front perspective view thereof; and,

FIG. 7 is a rear perspective view thereof.

FIG. 1

FIG. 2

FIG. 4

FIG. 3

FIG. 5

FIG. 6

FIG. 7
